Primary Examiner—Alan P. Douglas*Assistant Examiner*—A. D. Davis*Attorney, Agent, or Firm*—Leon Gilden[57] **CLAIM**

The ornamental design for a exhaust system pressure tester, as shown and described.

DESCRIPTION

FIG. 1 is a front elevational view of the exhaust system pressure tester showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front perspective view; and,

FIG. 8 is a rear perspective view thereof.

FIG. 1

FIG. 2

*FIG. 3**FIG. 4**FIG. 5**FIG. 6*FIG. 7

FIG. 8
